POCKET KNIFE OR SIMILAR ARTICLE

Albert M. Baer, New York, N. Y., assignor to Imperial Knife Company, Inc., Providence, R. I., a corporation of Rhode Island

Application February 20, 1956, Serial No. 40,222

Term of patent 14 years

(Cl. D22—3)

Fig. 1 is a side view of a pocket knife showing my new design;

Figs. 2 and 3 are bottom and end views, respectively, of said pocket knife.

The dominant features of the invention reside in the portions shown in full lines.

The side opposite to that shown in Fig. 1 presents a substantially similar appearance to Fig. 1.

I claim:

The ornamental design for a pocket knife or similar article, substantially as shown, and described.
